FIG. 1 is a front perspective view of an infant support structure with a rocking device of the present invention; FIG. 2 is left side view of FIG. 1;

FIG. 3 is a right side view of FIG. 1;

FIG. 4 is a top view of FIG. 1;

FIG. 5 is a bottom view of FIG. 1;

FIG. 6 is a front view of FIG. 1; and,

FIG. 7 is a rear view of FIG. 1.

The portions shown in phantom are for illustrative purposes only and form no part of the claimed design.
